UNITED STATES PATENT OFFICE.

CAP B. COLLINS, OF FRANKLIN, PENNSYLVANIA, ASSIGNOR TO COLLINS SAFETY RAZORS, OF CHICAGO, ILLINOIS, A COMMON LAW BUSINESS TRUST.

SPRING MOTOR.

Application filed February 24, 1920, Serial No. 360,887. Renewed June 16, 1928.

To all whom it may concern:

Be it known that I, CAP B. COLLINS, a citizen of the United States, residing at Franklin, in the county of Venango and State of Pennsylvania, have invented certain new and useful Improvements in Spring Motors, of which the following is a specification.

My invention concerns novel and advantageous improvements in spring-motors and concerns particularly, but not restrictedly, motors of this type whose speed is maintained substantially uniform or constant by a suitable governor or controller, such, for example, as one of the centrifugal type. Such motors are adapted for convenient and satisfactory employment in many relations, for instance in the handles of power-driven razors, telephone time-limit meters, and similar appliances. When used for actuating rotary razors, for example, the motor is housed in and operatively connected to a divided or sectional shell or casing and is wound up by turning one of such elements relatively to the other.

Various features of advantage also accrue from the particular manner of mounting and co-relating the various elements of the mechanism all of which will be readily understood from a study of the features of construction and operation of a preferred embodiment of the invention which has been fully illustrated in the accompanying drawing forming a part of this specification and throughout the views of which like reference characters refer to the same parts.

In this drawing:

Figure 1 is a fragmentary, central, vertical section through the motor and its casing or housing on line 1—1 of Figure 2;

Figure 2 is a horizontal section taken on line 2—2 of Figure 1, the manually-operable stop or brake being omitted.

Figure 3 is a horizontal section illustrating the retaining device in plan;

Figure 4 is a plan view of the centrifugal governor and

Figure 5 is a plan of the top frame member.

Referring to the drawing, it will be observed that the appliance includes a support-plate 10 of irregular shape connected at one or more of its three outstanding ears, as shown in Figure 2, to the inside of the one or upper element 11 of an enclosing

casing or housing. Mounted on such plate by a screw 14 is a sleeve 12 provided with a circular flange 13 lying on the top of plate 10 and into a threaded aperture of which the retaining screw 14 fits. Inside of sleeve 12 I provide a central, stationary post 15, the two parts 12 and 15 being fixedly secured together in any approved manner as by a transverse tapered pin 16.

Revolute on the stationary post 15 below the sleeve 12 I use a sleeve 17 which is held in position lengthwise on the post by the enlarged head of a screw 18 taking into a threaded hole 19 in the end of the post. Such sleeve 17 is turned to wind up the spring-motor as hereinafter indicated by means of an internally-threaded collar 20 screwed on a reduced, threaded, end portion of the sleeve, the circular or outstanding flange of such collar being secured as by soldering or otherwise to the inner face of the other or companion registered shell or casing member 22, the opposed housing elements 11 and 22 having a circular overlapping joint 23 at their edges. A nut 24 is screwed on to the part 21 of the sleeve 17 between a shoulder of the latter and the threaded collar 20, such nut holding in position a spring drum or barrel 25 having at one end a part 26 bearing on the nut 24 and revolute on the cylindrical portion of the sleeve. As is clearly illustrated in Figure 1 the barrel 25 has an internal circular shoulder 27 supporting a top disc 28 provided centrally with a round or annular flange 29 revolute on the sleeve 17 and bearing at its end against the side or under face of a ratchet-wheel 30 integral with the upper portion of such sleeve. It will be appreciated from an understanding of this construction that the nut 24 holds or maintains the elements 25 and 28 in proper assembled relation between itself and the enlargement 30 of the sleeve on which such drum is revolute.

This barrel or casing 25, 28 accommodates a flat coil-spring 31 within it, the inner portion of such spring being secured to the sleeve 17 at the points 32, 32, the outer end of the spring being fastened to the element 25 in any approved manner, not shown.

Co-operating with the teeth of the ratchet-wheel 30 I employ a suitably-shaped double-tooth pawl 33 pivoted at 34 on the under side of the main supporting plate 10.

100

110

The inner face of the cylindrical portion of member 25 extended beyond the member 23 is provided with an internal-gear 35 the teeth of which are in mesh with those of a small gear 36 on a shaft 37 revoluble in a suitable bearing in the plate 10 and an aligned bearing 38 in an upper supporting-plate 39 carried on a plurality of posts 40, 41 rising from the underlying plate 10. 10 Shaft 37 is equipped with a relatively-large gear 42 in mesh with the teeth of a gear 43, the teeth of which are cut in a duplex sleeve composed of two interfitted parts 80 and 81 secured together and accommodated between a portion of the post 15 and a hollow cylindrical part 82 of the fixed sleeve 12, a part of such element 82 being cut away at one side at 44 whereby the gear 42 may extend through such opening and be in co-operative relation with the teeth of the small gear 43. The portion 82 of the compound sleeve driven by the spring-motor by means of the mechanism designated may be employed to rotate any mechanism desired, 25 such, for instance, as the rotary-blade of a razor, but, of course, the particular means operated by such gear is of little importance so far as this invention is concerned.

To render the speed of rotation of the gears 42 and 43 uniform and substantially-unvarying, it is necessary to provide the mechanism with a suitable governor or controller and this comprises the following co-operating instrumentalities. Gear 42 is in mesh and drives a smaller gear 45 on a shaft 46 revoluble in bearings in the spaced supporting plates 10 and 39, and a gear 47 on such shaft revolves a smaller gear 48 on a shaft 49 in similar manner revoluble in bearings of the same two plates, such shaft being equipped with a gear 50 the teeth of which co-operate with those of a smaller gear 51 on a shaft 52 rotatable in bearings of the two plates, this shaft having thereon a spiral gear 53, the teeth of which are in co-active relation with an elongated spiral-gear 54 on a shaft 55 rotatable in bearings in ears or lugs 56 and 57 bent up from the plate 10, an end-thrust bearing 58 being provided 50 adjacent to the ear 57 against which the end of shaft 55 bears.

The speed of rotation of the gearing and consequently the control of the unwinding of the motor-spring 31 is effected by means 55 of a brake-mechanism which applies a restraining influence when the speed becomes too high and removes or decreases it when the speed is too low, thus rendering the rotation of the various shafts and gears substantially uniform.

To this end a relatively-stationary arm 59 is adjustable around its fulcrum or pivot pin 60 screwed into a threaded hole of the upper plate 39, such lever 59 being secured 65 in adjusted position by means of a screw 61

taking into a threaded hole of the plate 39 and extended through a slot 62 of the arm 59. At the free end of the latter above the shaft 55 it is equipped with a fiber or other friction block 63 adapted to bear against the side face of a friction brake disc 64 forming a part of a sleeve 65 slidably mounted on the shaft 55 and having a cavity 67 in an enlarged portion 66 accommodating a coil expansion-spring 68 bearing at one end 75 against a collar 69 fixed to the shaft 55 in any approved manner, as by pinning. The enlarged portion 66 of the slideable sleeve has two sets of spaced projections or lugs 70 between which weight arms 72, 72 are 80 fulcrumed or pivoted at 71, 71 each of such arms having a tail portion 73 adjacent to a circular flange 74 on the sleeve 69.

In order that the motor may be readily started and stopped, the housing or casing element 11 is slotted at 90 for the accommodation of a sliding finger-piece 91 roughened externally and frictionally held in position by means of a stud 92 secured thereto and extending inwardly through the opening 90, the threaded portion of the stem being equipped with a pair of nuts 93, 93 bearing on a washer 94 between which and the inner face of the shell or casing element is a washer of leather 95 or other suitable compressible material and a flat leaf-spring member 96 apertured for the accommodation of the stud and bent to provide an extension 97 adapted to be shifted into and out of engagement with the periphery of 100 the friction or brake disk 64.

The operation of the appliance will be readily understood from the detailed description of the construction and its various parts but may be summarized as follows:

To wind up the motor, the operator holds the casing element 11 in one hand and turns the other 22 relatively thereto, the rotation of the latter effecting the turning of the sleeve 17 and the winding of the spring by reason of the connections between them at 32, unwinding of the spring 31 being prevented by reason of the co-action of the pawl 33 with the ratchet-wheel 30 carried by such sleeve. As soon as the brake spring 97 is shifted away from the friction-disc 64 by sliding the finger-piece 91 in the proper direction in the slot 90 of the casing or housing element 11, the spring 31 will begin to unwind from its outer end, its inner end being held against rotation, and will revolve the barrel 25, 28 and its internal-gear 35, the rotation of which is transmitted through gear 36, shaft 37, and gears 42, 43 to the hollow shaft or sleeve element 80, 81, from which the power may be taken off to drive any mechanism desired.

The speed of rotation of these parts is, of course, controlled and regulated by the action of the centrifugally-operated weight-

arms 72, 72 which will be thrown out more or less depending upon the speed of rotation of shaft 55. If the speed becomes excessive, the feet 73 will engage the fixed flange 74 by reason of the outward movement of the arms 72 and pull the sleeve 65 to the left, as the parts are viewed in Figure 2, thus increasing the braking-pressure of the friction-disc 64 on the fiber or other element 63. As soon as the speed decreases below normal this pressure also diminishes because of the slight movement of the sleeve to the right, as is permitted through the movements of the portions 73 of the arms 72 relative to the flange 74. The train of gears which drives the shaft 75 from the gear 42 constitutes merely a speed increasing mechanism of usual type so as to make available a rate of rotation suitable and proper for the operation of a centrifugal-governor.

The invention is not limited or restricted to the precise and exact features of construction set forth in detail above and illustrated fully in the drawing, because these may be modified within comparatively wide limits without departure from the heart and essence of the invention and without the sacrifice of any of its substantial benefits and advantages.

I claim:

1. In an appliance of the character described, the combination of a casing composed of registering sections formed to overlap one another at their meeting edges and capable of rotation relatively to one another, a spring-motor carried by one of said sections, a shaft rotated by the unwinding of the spring of said motor, governing means to render the speed of rotation of said shaft substantially constant, and means to effect winding of the motor upon relative rotation of said sections, substantially as described.
2. In an appliance of the character described, the combination of a casing composed of registering sections capable of rotation relatively to one another, a spring-motor carried by one of said sections, a shaft rotated by the unwinding of the spring of the motor, means to effect winding of the motor upon relative rotation of said sections, a friction disc, a brake-shoe co-acting with said disc, a centrifugally-actuated weight, means to rotate said disc and weight by said motor, and means whereby said weight shifts said disc axially toward and from said brake-shoe, substantially as described.
3. In an appliance of the character described, the combination of a casing composed of registering sections capable of rotation relatively to one another, a spring-motor carried by one of said sections, a shaft rotated by the unwinding of the
4. In an appliance of the character described, the combination of a casing composed of registering sections capable of rotation relatively to one another, a spring-motor carried by one of said sections, a shaft rotated by the unwinding of the spring of the motor, means to effect winding of the motor upon relative rotation of said sections, a friction-disc, a lever, a brake-shoe carried by said lever and co-acting with the side of said disc, means permitting adjustment of the position of said lever and brake-shoe, a centrifugally-actuated weight, means to rotate said disc and weight from said motor, means whereby said weight shifts said disc axially toward and from said brake-shoe, and a manually-operable brake-element adapted to be moved into and out of frictional engagement with the edge of said disc, substantially as described.
5. In an appliance of the character described, the combination of a post, a sleeve revoluble on said post, a coil-spring having its inner end connected to said sleeve, means to turn said sleeve on the post to wind up the spring, means to prevent backward rotation of the sleeve on the post, a spring-barrel connected to the outer end of the spring and revoluble on said sleeve and rotated by the unwinding of the spring, a second sleeve on said post, and gearing connecting said barrel and second sleeve whereby the former rotates the latter including an internal-gear mounted on said spring-barrel, substantially as described.
6. In an appliance of the character described, the combination of a casing composed of registering sections capable of rotation relatively to one another, a post carried by one of said sections, a sleeve revoluble on said post and connected to the other casing section, a coil-spring in said sectional casing having its inner end connected to said sleeve, means to prevent backward rotation of the sleeve on the post, gearing operated by the outer end of the spring and rotated by the unwinding of the spring, a governor controlling the unwinding of the spring, and a second sleeve on said post revolved by said gearing, substantially as described.
7. In an appliance of the character described, the combination of a casing com-

spring of the motor, means to effect winding of the motor upon relative rotation of said sections, a friction-disk, a brake-shoe co-acting with said disc, a centrifugally-actuated weight, means to rotate said disc and weight from the motor, means whereby said weight shifts and disc axially toward and from said brake-shoe, and a manually-operated brake-element adapted to be moved into and out of frictional engagement with said disc, substantially as described.

4. In an appliance of the character described, the combination of a casing composed of registering sections capable of rotation relatively to one another, a spring-motor carried by one of said sections, a shaft rotated by the unwinding of the spring of the motor, means to effect winding of the motor upon relative rotation of said sections, a friction-disc, a lever, a brake-shoe carried by said lever and co-acting with the side of said disc, means permitting adjustment of the position of said lever and brake-shoe, a centrifugally-actuated weight, means to rotate said disc and weight from said motor, means whereby said weight shifts said disc axially toward and from said brake-shoe, and a manually-operable brake-element adapted to be moved into and out of frictional engagement with the edge of said disc, substantially as described.

5. In an appliance of the character described, the combination of a post, a sleeve revoluble on said post, a coil-spring having its inner end connected to said sleeve, means to turn said sleeve on the post to wind up the spring, means to prevent backward rotation of the sleeve on the post, a spring-barrel connected to the outer end of the spring and revoluble on said sleeve and rotated by the unwinding of the spring, a second sleeve on said post, and gearing connecting said barrel and second sleeve whereby the former rotates the latter including an internal-gear mounted on said spring-barrel, substantially as described.

6. In an appliance of the character described, the combination of a casing composed of registering sections capable of rotation relatively to one another, a post carried by one of said sections, a sleeve revoluble on said post and connected to the other casing section, a coil-spring in said sectional casing having its inner end connected to said sleeve, means to prevent backward rotation of the sleeve on the post, gearing operated by the outer end of the spring and rotated by the unwinding of the spring, a governor controlling the unwinding of the spring, and a second sleeve on said post revolved by said gearing, substantially as described.

7. In an appliance of the character described, the combination of a casing com-

posed of registering sections capable of rotation relatively to one another, a post carried by one of said sections, a sleeve revoluble on said post and connected to the other casing section, a coil-spring having its inner end connected to said sleeve, a ratchet-wheel rotated by said sleeve, a pawl co-operating with said ratchet-wheel to prevent backward rotation of the sleeve on the post, 10 a spring-barrel connected to the outer end of the spring and revoluble on said sleeve, a second sleeve on said post, and gearing connecting said spring-barrel and second sleeve whereby the motor revolves the latter, 15 the spring being wound up by the turning of one of said casing sections relatively to the other, substantially as described.

8. In an appliance of the character described, the combination of a relatively- 20 fixed post, an apertured sleeve fixed to and surrounding said post, a second revoluble driven sleeve between said post and sleeve having gear-teeth thereon, a third sleeve revoluble on said post, a coil-spring having 25 its inner end connected to said third sleeve, means to rotate said third sleeve to wind

up the spring, gearing connected to the outer end of said spring and projecting through the aperture of said first sleeve and in mesh with the gear of said second sleeve, and a 30 governor controlling the speed of rotation of said driven sleeve, substantially as described.

9. In an appliance of the character described, the combination of a casing composed of registering sections capable of rotation relatively to one another, a post mounted on one of said sections, an apertured sleeve fixed to and surrounding said post, a second revoluble driven sleeve 40 between said post and sleeve having gear teeth thereon, a third sleeve revoluble on said post and operatively connected to the other casing section, a coil-spring having its inner end connected to said third sleeve, gearing 45 connected to the outer end of said spring and projecting through the aperture of said first sleeve and in mesh with the gear of said second driven sleeve, and a governor controlling the speed of rotation of said driven sleeve, substantially as described.

CAP B. COLLINS.
